SEPTIC TANK

Decio Torricelli, Springfield, Mass.

Application October 7, 1944, Serial No. 557,709

5 Claims. (Cl. 210—6)

1

This invention relates to septic tanks and is directed to improvements in septic tanks formed from pre-cast components.

The principal objects of the invention are directed to the provision of a septic tank construction wherein a tank having single or plural compartments may be formed by cooperating pre-cast sections.

Various novel objects and advantages of the invention will be hereinafter observed in connection with the accompanying description of the invention with reference to the accompanying drawing wherein:

Figs. 1 to 4 inclusive are perspective views of the bottom, side, end and partition wall members forming a part of the invention;

Figs. 5 and 6 are perspective views showing end and center upper wall or cover members;

Figs. 7 and 8 are plan and side elevational views respectively showing a single compartment tank of the invention; and

Figs. 9 and 10 are plan and side elevational views respectively showing a double compartment tank of the invention.

Referring now to the drawing more in detail, the invention will be fully described.

The various components to be described are preferably cast from concrete or a cement mixture in suitable molding equipment and the components may be reinforced with metal if desired.

A bottom wall 2 is shown in Fig. 1 which has longitudinal and transverse wall receiving grooves 4 and 6 on the outer sides of which there are beads 8 and 10.

A side wall 12 is shown in Fig. 2 which may be called a rear wall. On the upper edge of the wall there are notches 14' and a projection 16. A groove 18 extends downwardly from the upper edge thereof for receiving an edge of a baffle 17 and a groove 20 extends upwardly from the lower edge for receiving one end of a cross plate 21.

As stated, the wall 12 shown is a rear wall and a front wall 14 similar thereto is provided which has grooves corresponding to the grooves 18 and 20 for receiving an edge of a baffle 19. The front and rear walls constitute a pair of right and left hand walls.

An end wall 30 is shown in Fig. 3 which has side grooves 32 for receiving the end edges of the front and rear walls 12 and 14. A groove 34 extends downwardly from the upper edge for receiving a vertical edge of baffle 17. There are two similar end walls the other one being indicated by 36 and this wall 36 has a groove for

receiving a vertical edge of baffle 19. These end walls are right and lefts.

In setting up a tank having a single compartment, the side walls 12 and 14 are vertically disposed relative to the bottom wall 2 with their lower edges in the grooves 4 and 6 thereof.

The end walls 30 and 36 have their lower edges in the grooves 6 of the bottom wall 2 and the vertical edges of the side walls are disposed in the vertical grooves such as 32 of the end walls. The cross plate 21 has its opposite ends disposed in the grooves such as 20 of the side walls 12 and 14.

Baffles 17 and 19 have opposite vertical edges in the vertical grooves of the side and end walls so as to extend diagonally across the corners of the compartment, as shown in Fig. 7, to provide vertically disposed passageways.

An auxiliary baffle 23 vertically disposed is located between the baffle 19 and side wall 14.

An end cover plate 40 shown in Fig. 5, has grooves 42 and 44 for receiving the upper edges of an end wall and the upper edges of the side walls. There are two such end cover plates, one for each end of the tank and when in place on the side and end walls said walls are held thereby in the desired relative position.

The grooves are made large enough to loosely receive the edge portions of their respective components and when the walls are assembled as described the joints may be pointed up inside and outside the compartment in the usual manner.

The member 40 may have ribs such as 46 which are adapted to reinforce the said member. Portions 43 are receivable in the notches 14'.

The end wall 30 has an opening 50 behind baffle 17 and the opposite end wall 36 has an opening 52 similar thereto. The opening 52 may function as the inlet and sewage entering therethrough flows downwardly at the rear of baffle 19 up and over cross plate 21 and upwardly behind baffle 17 to opening 50.

Sludge strikes against cross plate 21 and as solid particles are liquified sludge or unliquified material rises or at least remains in the compartment while water flows out outlet 50. The arrangement of the baffles and cross plate prevents solids and sludge from passing out of the tank and to accomplish this the cross plate may be located at any point longitudinally of the compartment.

A center cover plate is shown in Fig. 6 and is indicated by 60. It has end grooves 62 for receiving the upper edges of the portions 16 of the side walls and may have reinforcing ribs 61.

When it is desired to form a double compart-

ment tank there is provided a partition or intermediate end wall 70 shown in Fig. 4.

This wall 70 has vertical grooves 72 for receiving adjacent end edges of adjacent side walls 12 and 14. A groove 74 along the lower edge of wall receives the beads 8 of adjacent bottom walls, as shown in Fig. 1 with parts 76 in the grooves 6 of said lower walls so as to hold or lock the lower walls together. A groove 80 in the upper edge of the wall 70 forms part 82 which are received in the grooves 44 of the end cover plates 40. An opening 84 is provided in the lower portion of the wall 70.

The double compartment tank is shown in Figs. 9 and 10.

The bottom, side, intermediate and end walls are assembled together with the cross plates and baffles and pointed up as previously described and the cover members are put in place so as to provide a double compartment tank.

The sewage enters the left hand end as in the case of Figs. 7 and 8, and flows over cross plate 21 through wall member 70 over the other cross plate and up through the passageway formed by baffle 70 and out the outlet 50.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A septic tank comprising in combination, a bottom wall provided with longitudinal and transverse grooves adjacent opposite and adjacent edges thereof, end and side walls having lower edges disposed in said grooves and extending upwardly from said bottom wall, said end walls having vertically extending grooves in which the end edges of the side walls are disposed, baffles extending downwardly from upper edges of adjacent side and end walls disposed diagonally relative to said adjacent side and end walls to form therewith vertically disposed passageways terminating upwardly from said bottom wall, said end walls provided with openings leading into said passageways, said side walls provided on the upper edges thereof with upwardly extending central projections intermediate the ends thereof and notches at the opposite ends of the projections, end cover members having grooves in the lower faces thereof receiving the upper edges of said end walls and adjacent upper edges of said side walls and provided with portions at the ends of certain of said grooves disposed in said notches, and a central cover member having grooves in the lower face thereof in which the projections of the side wall are receivable and provided with ribs adjacent the ribs of the end cover members, said cover members closing the tank and overlying the upper ends of said passageways.

2. A septic tank comprising in combination, a pair of horizontally disposed adjacent bottom walls each having longitudinal and transverse grooves adjacent opposite and adjacent edges thereof, a central vertically disposed intermediate wall above the jointure of said bottom walls ex-

tending vertically upwardly therefrom having portions disposed in the adjacent transverse grooves of said bottom walls and provided with a transverse groove on the upper edge thereof and vertical grooves on its opposite faces adjacent opposite vertical sides thereof, end walls having lower edges in the outermost transverse grooves of the bottom walls and provided with grooves adjacent vertical edges thereof, side walls having lower edges in the longitudinal grooves of the bottom walls and opposite end edges in the grooves of the end walls and intermediate wall, said side walls having upwardly extending projections on the upper edges thereof and notches at opposite ends of said projections, end cover members having grooves in the lower faces thereof in which the upper edges of the end walls and adjacent portions of the side walls are receivable and provided with portions at the ends of certain of the grooves receivable in the notches of the side walls adjacent said end walls, other cover members having grooves receiving the upper edges of adjacent side walls provided with portions at the ends of certain of said grooves disposed in the groove on the upper side of the central intermediate wall and in the notches of the side walls, and central cover members having grooves on the lower faces thereof at their opposite ends in which the projections of the side wall are disposed, said end and intermediate walls provided with openings therethrough for the passageway of liquid into and out of said tank.

3. A septic tank comprising in combination, a pair of horizontally disposed adjacent bottom walls each having longitudinal and transverse grooves adjacent opposite and adjacent edges thereof, a central vertically disposed intermediate wall above the jointure of said bottom walls extending vertically upwardly therefrom having portions disposed in the adjacent transverse grooves of said bottom walls and provided with a transverse groove on the upper edge thereof and vertical grooves on its opposite faces adjacent opposite vertical sides thereof, end walls having lower edges in the outermost transverse grooves of the bottom walls and provided with grooves adjacent vertical edges thereof, side walls having lower edges in the longitudinal grooves of the bottom walls and opposite end edges in the grooves of the end walls and intermediate wall, said side walls having upwardly extending projections on the upper edges thereof and notches at opposite ends of said projections, end cover members having grooves in the lower faces thereof in which the upper edges of the end walls and adjacent portions of the side walls are receivable and provided with portions at the ends of certain of said grooves in the notches of the side walls adjacent said end walls, other cover members having grooves receiving the upper edges of adjacent side walls and provided with portions at the ends of certain of said grooves disposed in the groove on the upper side of the central wall and in the notches of the side wall, central cover members having grooves on the lower faces thereof in which the projections of the side wall are disposed, and baffles at opposite ends of the tank disposed diagonally relative to adjacent portions of said side and end walls and extending downwardly from upper edges of said side and end walls to form with said side and end walls vertical passageways terminating upwardly from said bottom walls, said end walls adjacent upper edges thereof provided with openings leading into said passageways, and said intermediate wall pro-

vided with an opening therethrough adjacent said bottom walls.

4. A septic tank comprising in combination, a pair of horizontally disposed adjacent bottom walls each having longitudinal and transverse grooves adjacent opposite and adjacent edges thereof, a central vertically disposed intermediate wall above the jointure of said bottom walls extending vertically upwardly therefrom having portions disposed in the adjacent transverse grooves of said bottom walls and provided with a transverse groove on the upper edge thereof and vertical grooves on its opposite faces adjacent opposite vertical sides thereof, end walls having lower edges in the outermost transverse grooves of the bottom walls and provided with grooves adjacent vertical edges thereof, side walls having lower edges in the longitudinal grooves of the bottom walls and opposite end edges in the grooves of the end walls and intermediate wall, said side walls having upwardly extending projections on the upper edges thereof and notches at opposite ends of said projections, end cover members having grooves in the lower faces thereof in which the upper edges of the end walls and adjacent portions of the side walls are receivable and provided with portions at the ends of certain of said grooves receivable in the notches of the side walls adjacent said end walls, other cover members having grooves receiving the upper edges of adjacent side walls and provided with portions at the ends of certain of said grooves receivable in the groove on the upper side of the central wall and in the notches of the side walls, central cover members having grooves on the lower faces thereof at their opposite ends in which the projections of the side walls are disposed, baffles at opposite ends of the tank disposed diagonally relative to adjacent portions of said side and end walls and extending downwardly from upper edges of said side and end walls to form with said side and end walls vertical passageways terminating upwardly from said bottom walls, said end walls adjacent upper edges thereof provided with openings leading into said passageways, and said intermediate wall provided with an opening therethrough adjacent said bottom walls, and cross plates extending upwardly from said bottom walls and between said side walls intermediate said end and central wall terminating upwardly from said bottom walls.

5. A septic tank comprising in combination, a

pair of horizontally disposed adjacent bottom walls each having longitudinal and transverse grooves adjacent opposite and adjacent edges thereof, a central vertically disposed intermediate wall above the jointure of said bottom walls extending vertically upwardly therefrom having portions disposed in the adjacent transverse grooves of said bottom walls and provided with a transverse groove on the upper edge thereof and vertical grooves on its opposite faces adjacent opposite vertical sides thereof, end walls having lower edges in the outermost transverse grooves of the bottom walls and provided with grooves adjacent vertical edges thereof, side walls having lower edges in the longitudinal grooves of the bottom walls and opposite end edges in the grooves of the end walls and intermediate wall, said side walls having upwardly extending projections on the upper edges thereof and notches at opposite ends of said projections, end cover members having grooves in the lower faces thereof in which the upper edges of the end walls and adjacent portions of the side walls are receivable and provided with portions at the ends of certain of said grooves disposed in the notches of the side walls adjacent said end walls, other cover members having grooves receiving the upper edges of adjacent side walls and provided with portions at the ends of certain of said grooves disposed in the groove on the upper side of the central wall and in the notches of the side walls, central cover members having grooves on the lower faces thereof in which the projections of the side walls are disposed, baffles at opposite ends of the tank disposed diagonally relative to adjacent portions of said side and end walls and extending downwardly from upper edges of said side and end walls to form with said side and end walls vertical passageways terminating upwardly from said bottom walls, said side and end walls adjacent upper edges thereof provided with openings leading into said passageways, cross plates extending upwardly from said bottom walls and between said side walls intermediate said end and central wall having upper edges terminating in a horizontal plane disposed upwardly from said bottom walls, and said intermediate wall provided with an opening therethrough which is disposed below the horizontal plane of the upper edges of said cross plates.

DECIO TORRICELLI.
